ARM CHAIR

Leo Jiranek, Old Greenwich, Conn., assignor to Heywood-Wakefield Company, Gardner, Mass., a corporation of Massachusetts

Application September 10, 1956, Serial No. 42,896

Term of patent 7 years

(Cl. D15—1)

Fig. 1 is a front perspective view of an arm chair showing my new design;

Fig. 2 is a top plan view thereof;

Fig. 3 is a fragmentary sectional view on the line 3—3 of Fig. 1 but on a scale enlarged with respect thereto; and

Fig. 4 is a fragmentary view in elevation on the line 4—4 of Fig. 3.

I claim:

The ornamental design for an arm chair, substantially as shown.
